UNITED STATES PATENT OFFICE.

CHESTER E. TUELL, OF WASHINGTON, DISTRICT OF COLUMBIA.

COLLAPSIBLE CRATE.

Application filed April 18, 1922. Serial No. 555,062.

To all whom it may concern:

Be it known that CHESTER E. TUELL, citizen of the United States, residing at Washington, in the District of Columbia, has invented certain new and useful Improvements in Collapsible Crates, of which the following is a specification.

This specification has reference to a folding crate, and more specially relates to a crate suitable for shipping chickens and the like.

One important object of the invention is to improve the general construction of devices of this character.

15 A second important object of the invention is to provide a novel arrangement of dowel pins and sockets for holding the top of the crate in position both when the crate is set up and when it is collapsed.

20 A third important object of the invention is to provide an improved corner arrangement for such crates.

With the above and other objects in view, the invention consists in general of certain 25 novel details of construction and combinations of parts hereinafter fully described, illustrated in the accompanying drawings, and specifically claimed.

In the accompanying drawings, like characters of reference indicate like parts in the several views, and:—

Figure 1 is a perspective view of the crate in its set up position.

Figure 2 is a side elevation of the crate 35 collapsed.

Figure 3 is a detail section showing the corner arrangement in this crate.

Figure 4 is a detail section showing the dowel pin arrangement with the crate set up.

40 Figure 5 is a view similar to Figure 4 with the crate collapsed.

In the construction of this invention there is provided a bottom 10 at each corner of which is mounted a hinge plate which consists of a strip of metal split to provide a pair of legs 11, the metal beyond the split portion being indicated at 12 and bent back upon the legs. The legs are then bent to extend away from this portion and the portion 50 12 is also bent so that one leg extends at right angles to the other. This portion 12 is provided with lower opening 13 and an upper opening 14. The lower opening 13 receives the reduced end 15 of lower side frame members 16 which are connected to the upper side frame members 17 by slats 18. The

upper openings receive the reduced end 19 of lower end frame members 20 which are connected to upper frame members 21, by slats 22. With this construction the sides 60 can fold down on the bottom 10 and the ends can then fold down on the end portions of said sides. In the tops of the members 21 are formed dowel pin sockets 23 and correspondingly placed sockets 24 are formed in 65 the outside space of each member 20. Likewise the members 17 are provided with dowel pin sockets 25 in their top spaces.

The top of this crate consists of a rectangular frame having side frame members 70 26 and end frame members 27. From the under side of these members dowel pins 28 project downwardly so as to enter the openings 23 and 25 when the crate is set up or the openings 24 when the crate is collapsed. 75

Between the end members 27 extend intermediate members 29 and secured to these intermediate members adjacent each end are clips 30 which engage in notches 31 of the members 21 when the crate is set up or in 80 notches 32 when the crate is collapsed. At each corner of the top is a corner brace 33 which depends from the top so as to engage the corners of the side and end frames both when the crate is set up and when it is collapsed. 85

When the crate is set up the top is placed in the position showing Figure 1, and, in the position showing in Figure 1, and, owing to the dowel pins and corner 90 and end frames against accidental collapsing. In like manner when the crate is collapsed the top with its dowel pins, clips and corner braces will hold the parts together in such manner as to prevent breakage during 95 shipment.

There has thus been provided a simple and efficient device of the kind described and for the purposes specified.

It is obvious that minor changes may be 100 made in the form and construction of the invention without departing from the material principles thereof. It is not therefore desired to confine the invention to the exact form herein shown and described, but it is 105 wished to include all such as properly come within the scope claimed.

Having thus described the invention, what is claimed as new, is:—

1. In a folding crate, a bottom, side frame 110 members hinged at their bottom portions to the crate bottom and foldable inward there-

on, end frame members hinged at their bottom portions to the ends of said bottom and foldable on the side frame members, said end frame members having dowel pin sockets 5 in their top edges and correspondingly placed dowel pin sockets in their outer faces adjacent their bottom edges, and a top having depending dowel pins at its ends arranged to enter the sockets on the edges of the 10 crate ends when the crate is set up and to enter the sockets on the outer faces of said ends when the crate is collapsed.

2. In a folding crate, a bottom, side frame members hinged at their bottom portions to 15 the crate bottom and foldable inward thereon, end frame members hinged at their bottom portions to the ends of said bottom and foldable on the side frame members, said end frame members having dowel pin sockets 20 in their top edges and correspondingly placed dowel pin sockets in their outer faces adjacent their bottom edges, a top having depending dowel pins at its ends arranged to enter the sockets on the edges of the 25 crate ends when the crate is set up and to enter the sockets on the outer faces of said ends when the crate is collapsed, and clips carried by 30 said top and engaged in the ends in both set up and collapsed positions whereby to hold the top securely on the remainder of the crate in either of said positions, and corner plates depending from the corners of said top and engaging the ends and sides of the 35 crate in both set up and collapsed positions.

3. In a folding crate, a bottom, side frame members hinged at their bottom portions to the crate bottom and foldable inward thereon, and frame members hinged at their bot-

tom portions to the ends of said bottom and foldable on the side frame members, said end frame members having dowel pin sockets in their top edges and correspondingly placed dowel pin sockets in their outer faces 40 adjacent their bottom edges, a top having depending dowel pins at its ends arranged to enter the sockets on the edges of the crate ends when the crate is set up and to enter the sockets on the outer faces of said ends 45 when the crate is collapsed, clips carried by said top and engaged in the ends in both set up and collapsed positions whereby to hold the top securely on the remainder of the crate in either of said positions, and corner 50 plates depending from the corners of said top and engaging the ends and sides of the crate in both set up and collapsed positions.

4. In a collapsible crate, a bottom, a hinge plate at each corner of said bottom consisting of a body having two portions disposed at right angles to each other and legs extending from said body portion along the edge portions of the ends and sides of the bottom and being secured thereto, said body 60 having openings in the two portions thereof, crate sides having lower members provided with reduced ends each fitting an opening in a respective hinge plate, crate ends having lower members provided with reduced ends 65 each fitting a second opening in a respective hinge plate, and a top detachably connected to said ends and sides.

In testimony whereof I affix my signature.
CHESTER E. TUELL.
